BLOOD DRAWING INSTRUMENT

John C. Soet, Grand Rapids, Mich.

Application July 25, 1946, Serial No. 686,250

6 Claims. (CL 128—276)

1

This invention pertains to surgical instruments and relates more particularly to improvements in blood drawing instruments.

The particular problem to which this invention is addressed is that of obtaining sizable samples of human blood for pathological analysis and under conditions where a large number of samples must be taken by a single physician or technician within a given period of time and with a minimum of inconvenience and delay with respect to the donor. This invention finds outstanding utility in the medical departments of large industrial plants where syphilitic examination of a great number of persons is required.

Blood drawing instruments for this purpose comprise an evacuated vial or glass tube for receiving the blood, a tubular needle for withdrawing the blood from the vein of a person and conducting it into the vial or tube, and preferably, some form of means for holding the vial or tube and the needle in an operative relation.

It is the general purpose of this invention to provide a simple blood drawing instrument of this type which may be used with a maximum of convenience and speed and therefore possess, to a high degree, surgical maneuverability, which is a primary essential for the purposes outlined.

It is one of the objects of this invention to provide a blood drawing instrument of the type described in which the means for holding the blood vial and tubular needle are constructed and arranged so that these parts may be detachably retained and released upon completion of the blood drawing operation with an absolute minimum of effort.

A specific feature of improvement resides in the provision of an instrument comprising an elongated handle with a head portion extending laterally from one end thereof and provided with resilient needle-clamping means which may be instantly operated by the touch of a finger.

In a more specific aspect, it is a further object of this invention to provide in combination with a blood drawing instrument having a handle and means for detachably supporting a blood vial for reciprocation along the handle to receive one end of the tubular needle, a resilient needle-clamping means which includes a plunger extending from one end of the handle and formed and arranged to cooperate with a formed portion of the handle releasably to engage the needle by a collar fixed intermediate its end and to maintain the needle against movement in any direction. Still more specifically, it is intended to provide in this novel combination a button releasing means for the

2

plunger of the clamping means so that the collar of the needle may be engaged or released so as to fall free of the handle by a light touch of a finger.

5 Further novel features of improvement contributing to ease and speed in operation and simplifying the construction of instruments of this nature will be apparent and readily understood from the following detailed description of 10 an illustrative embodiment of the invention, taken in connection with the accompanying drawings, in which:

Fig. 1 is a perspective view showing the assembled blood drawing instrument in the hands 15 of a user as the needle is being mounted on the handle;

Fig. 2 is a perspective view of the instrument in use with the needle inserted in a vein of the 20 arm of a donor and the blood vial in cooperative position to receive blood conducted by the needle;

Fig. 3 is a side elevation, partly in section, of the completely assembled instrument of this invention, the section being along the line 3—3 of Fig. 6;

25 Fig. 4 is a partial side elevation of the head portion of the instrument handle with a needle engaged by the needle-clamping means;

Fig. 5 is a front elevation of the handle and needle shown in Fig. 4;

30 Fig. 6 is a section of the head portion of the handle and a clamped needle, as seen along the line 6—6 of Fig. 3;

Fig. 7 is a cross-sectional view of the assembled 35 instrument taken on the line 7—7 of Fig. 3, and

Fig. 8 is a perspective view showing the handle of the instrument in the hand of a user, the needle having just been released by the needle-clamping means.

Referring particularly to Figs. 1, 2 and 3, the 40 numeral 10 refers to the complete instrument which includes an evacuated blood vial 12 having a perforable rubber stopper 13 arranged for reception of a needle 14 which is of the tubular hypodermic type.

45 The vial 12 and needle 14 are supported in operative relation by an elongated instrument handle 16 provided with sliding carriage means 18 for the vial and quick-release needle-clamping means 20 carried by a head portion 22 of the handle and constructed and arranged to cooperate with this head portion in releasably engaging a collar 24 which is secured to the needle 14 intermediate its length.

The carriage means 18, which is appreciably 50 shorter than either the vial 12 or handle 16, in-

cludes a pair of inturned depending legs 26, 28 (Fig. 7) forming therewith a channel and slidably engaging suitably shaped angular, longitudinal track grooves 28, 28 formed in opposite sides of the instrument handle 16. The free ends of the track groove formations have depressed end corners 30, 30 (Fig. 3) for preventing separation of the carriage 18 from the handle 16. On its outer side the sliding carriage 18 is provided with a longitudinally spaced pair of spring clips 32 for detachably engaging the blood vial 12, and with an end abutment or stop 34 for the bottom or closed end of the vial.

Particular attention is now directed to the details of construction and the arrangement of the head portion 22 and the needle-clamping means 20. These details are shown best in Figs. 3, 4, 5, 6 and 8. Figs. 3 and 6 indicate that the head portion 22 extends laterally from one end of the instrument handle 16 and on the side which supports the carriage means 18, so that the needle 14 will engage and perforate the rubber stopper 13 of the evacuated vial 12 when the latter is slid forwardly to the position shown in Fig. 2.

The head portion 22 is formed with the lengthwise extending, through bore 36 accommodating at its extending end an outwardly projecting plunger 38 of generally hook shape for engaging the needle collar 24, and at its handle base end a releasing or operating button 40. A small connecting rod 42 joins the plunger 38 and button 40 within the head portion 22 and is encircled by a compression spring 44 which engages the inner concealed end of button 40 and a transverse pin 46 which extends through the bore adjacent one side of the rod 42 as shown in Figs. 3 and 6. The function of the pin 46, which is supported at its ends by the head portion 22, is to provide a fixed abutment on one end of the compression spring 44 so as to normally maintain the hook-shaped plunger 38 in retracted clamping position, from which it may be released by pushing the button 40 inwardly against the spring 44. Preferably the clamping means 20 is held against rotation from the position shown by flattening the adjacent sides of the connecting rod 42 and the transverse retaining pin 46 (Fig. 6).

With reference to Figs. 4, 5 and 8, it will be observed that the head portion 22 is provided with a transverse slot 48 which is only slightly longer than the needle collar 24, which it receives, and that the adjacent sides of the generally rectangular head portion are formed with longitudinally aligned needle notches 50, 50 for receiving the needle 14 at opposite ends of the collar 24. These notches 50, 50 are formed with vertical faces 54, 54 on their inner sides and inwardly inclined faces 56, 56 on their outer sides, said inclined faces terminating a short distance above the bottoms of the notches and the corresponding outer end of the head portion 22 being slightly shorter than that defined by the tops of the vertical faces 54, 54.

The generally hook-shaped plunger 38 has a special configuration for efficient cooperation with the collar 24. As shown in Fig. 6, the plunger 38 has a flat top 58 merging with a larger and generally vertical concave surface 60 complementary to the circular cross section of the knurled collar 24 and terminating in a bottom, curved slope portion 62. The flat top portion 58, complementary concave surface 60 and the bottom, curved slope portion 62 cooperate with the transverse slot 48 and aligned notches 50, 50 of the head portion 22 to maintain the needle in

fixed operative relation to the handle 16 and at the same time permit it to be quickly released and fall freely when the operating button 40 is depressed (Fig. 8), with curved slope portion 62 tending to roll the collar out of the plunger 38.

The importance of the novel features of the instrument of this invention and its particular advantages will be clearly understood from the following description of a typical blood drawing operation. Fig. 1 shows the manner of grasping the handle 16 of the instrument for insertion of a sterile needle 14 into the clamping means 20 carried by the head portion 22. The handle 16 is held on opposite side faces by the thumb and 15 second, third and fourth fingers, respectively, of the right hand of a physician or other technician. The fourth finger of this right hand naturally falls into a position for engaging and depressing the button 40 on the bottom or base of the handle 16 for releasing the needle-clamping means 20 and permitting the needle collar 24 to be inserted from below by the left hand of the person using the instrument. When the collar has been so inserted and aligns with the hook-shaped plunger 38 and the slot 48 of the head portion 22, release 20 of the operating button 40 is all that is necessary to lock the needle in a fixed position with respect to the handle 16. While Fig. 1 shows the evacuated blood vial 16 already in place on the carriage means 18, it may be found preferable to mount or 25 clamp the needle to the head portion 22 before the evacuated vial 12 with its perforable sealing means or stopper 13 is added.

The carriage means 18 and the attached vial 30 12 will not be advanced from the retracted position shown in Figs. 1 and 3 until after the lumen of the needle 14 is just underneath the skin but not into the vein of the donor. Then the blood vial is pushed forward along the handle 16 by 35 means of the carriage stop portion 34, which may be engaged by the end of the thumb of the left hand of the physician or technician, as clearly shown in Fig. 2. The instrument is then advanced forward by the right hand gripping the handle 16 so that the needle is caused to enter the vein and the blood runs into the evacuated vial 12, the parts being in the relative positions 40 of Fig. 2. After the blood vial 12 is filled, the needle is withdrawn out of the vein by pulling 45 the whole instrument 10, after which the blood vial 12 and carriage 18 are pulled back into their original position and the former removed from the instrument. Without materially changing the position in which the right hand grasps the 50 thumb of the instrument 10, or even so much as rotating the instrument appreciably about its longitudinal axis, the used needle 14 may be quickly dropped clear of the instrument by merely depressing the operating button 40 with a 55 light touch of the forefinger of the right hand. Then, without appreciable delay or loss of time, the whole operation may be repeated on the next 60 donor.

The blood drawing instrument of this invention has been used on thousands of patients with a minimum of discomfort and annoyance and with a rapidity of operation that has made it possible to maintain routine blood tests of large groups in venereal control clinics where it would not have otherwise been possible because of the time required of both technicians and patients.

Having thus described my invention what I claim as novel and desire to secure by Letters Patent of the United States is:

1. A blood drawing instrument comprising an

elongated handle having a head portion extending laterally from one end thereof, carriage means reciprocable longitudinally of the handle on the side toward which the head portion extends, a blood vial detachably engaged by the carriage means for reciprocation therewith and having perforable sealing means at the end adjacent the head portion, a needle adapted to perforate said sealing means and conduct blood into the vial, and resilient needle-clamping means cooperable with the head portion of the handle releasably to engage the needle intermediate its length and maintain it against longitudinal movement with one end in position to perforate the sealing means when said sealing means is reciprocated into engagement therewith, said needle-clamping means and head portion being constructed and arranged to discharge the needle from one side of the head portion.

2. A blood drawing instrument comprising an elongated handle having a head portion extending laterally from one end thereof; carriage means reciprocable longitudinally of the handle on the side toward which the head portion extends; a blood vial detachably engaged by the carriage means for reciprocation therewith and having perforable sealing means at the end adjacent the head portion; a needle adapted to perforate said sealing means and conduct blood into the vial; and resilient needle-clamping means cooperable with the head portion of the handle releasably to engage the needle intermediate its length and maintain it against longitudinal movement with one end in position to perforate the sealing means when said sealing means is reciprocated into engagement therewith, said needle clamping means and head portion being constructed and arranged to discharge the needle from one side of the head portion.

3. A blood drawing instrument comprising an elongated handle having a head portion extending laterally from one end thereof; carriage means reciprocable longitudinally of the handle on the side toward which the head portion extends, said head portion being formed to provide a bore extending lengthwise thereof; a blood vial detachably engaged by the carriage means for reciprocation therewith and having perforable sealing means at the end adjacent the head portion; a needle adapted to perforate said sealing means and conduct blood into the vial; and resilient needle-clamping means including a plunger in the bore of said head portion and cooperable with one end of the head releasably to engage the needle intermediate its length and maintain one end of the needle in position to perforate the sealing means when said sealing means is reciprocated into engagement therewith, and plunger operating means projecting from the other end of the head portion.

4. A blood drawing instrument comprising an elongated handle having a head portion extending laterally from one end thereof; carriage means reciprocable longitudinally of the handle on the side toward which the head portion extends, said head portion being formed to provide a bore extending lengthwise thereof; a blood vial detachably engaged by the carriage means for reciprocation therewith and having perforable sealing means at the end adjacent the head portion; a needle adapted to perforate said sealing means and conduct blood into the vial; and needle-clamping means including a plunger in the bore of said head portion shaped and arranged to co-

operate with one end of the head portion releasably to hold the needle when the needle is positioned to perforate the sealing means as said sealing means advances with the carriage means into engagement therewith, plunger operating means projecting from the other end of the head portion, and spring means arranged within the bore of said head portion to bias the plunger into clamping position and the operating means into projecting position.

5. A blood drawing instrument comprising an elongated handle having a head portion extending laterally from one end thereof, said head portion being formed to provide a bore extending lengthwise thereof; carriage means secured to the handle and slidably longitudinally thereof; a blood vial detachably secured to the carriage means and having perforable sealing means at the end adjacent the head portion; a needle provided with a collar intermediate its length and adapted to perforate said sealing means and conduct blood into the vial; and needle-clamping means including a plunger in the bore of said head portion formed with a hook-shaped end generally complementary to and slightly larger than the collar of the needle, a plunger operating button projecting from the other end of the head portion, and spring means arranged within the bore of said head portion to bias the plunger into retracted clamping position and the operating button into projecting position, said head portion being formed with spaced aligned notches for receiving the needle at opposite ends of the collar and a transverse slot opposite the hook-shaped end of the plunger and slightly longer than the collar, said slot permitting lateral insertion and withdrawal of the needle collar when the needle is out of the notches and preventing longitudinal shifting of the needle when clamped.

6. In a blood drawing instrument, the combination comprising an elongated handle having a head portion extending laterally from one end thereof, said head portion being formed to provide a bore extending lengthwise thereof; carriage means slidably secured to the handle for movement longitudinally thereof, said carriage means being constructed and arranged detachably to secure thereto on the side of the handle toward which the head portion extends, a blood vial having perforable sealing means at the end adjacent the head portion; and needle-clamping means including a plunger arranged in the bore of said head portion for cooperative engagement with a needle provided with a collar intermediate its length and adapted to perforate said sealing means and conduct blood into the vial, said plunger being formed with a hook-shaped end generally complementary to and slightly larger than the collar of the needle, a plunger operating button projecting from the other end of the head portion, and spring means arranged within the bore of said head portion to bias the plunger into retracted clamping position and the operating button into projecting position, said head portion being formed with spaced aligned notches for receiving the needle at opposite ends of the collar and a transverse slot opposite the hook-shaped end of the plunger and slightly longer than the collar, said notches and slot permitting lateral insertion and withdrawal of the needle collar when the needle is out of the bottoms of the notches and preventing longitudinal shifting of the needle when clamped.

JOHN C. SOET.
